ABSTRACT OF THE DISCLOSURE

A low-pressure sodium vapor lamp is surrounded by an evacuated outer envelope and is provided with a protuberance in which an amount of sodium which is not in vapor form is present during operation of the lamp, this protuberance being heated only by the heat evolved in the discharge tube. This makes possible a highly-loaded lamp because the sodium pressure is determined by the temperature of the protuberance which is lower than that of the lamp but not too low because it is heated by the lamp.

This invention relates to a low-pressure sodium vapour discharge lamp comprising a discharge tube and an outer bulb surrounding it, wherein the space between the discharge tube and the outer bulb is substantially exhausted and wherein an amount of sodium which is not in vapour form in the operating condition of the lamp is present in a protuberance of the discharge tube, which protuberance is heated only by the heat evolved in the discharge tube.

The term "substantially exhausted" is to be understood to mean a pressure which is lower than approximately 10^{-3} torr.

In a known lamp of the kind above referred to, the discharge tube. The elevations form, as it were, contain form of small shallow elevations which serve to prevent the sodium from being distributed unevenly over the discharge tube. The elevations form, as it were, containers which ensure that sodium drops cannot be displaced or hardly. (This is the so-called blocking function.) The temperature prevailing in the elevation is a little lower than that in the other portions of the discharge tube. The blocking function for the sodium is even enhanced by this slightly lower temperature, since in practice sodium will not now be evaporated from an elevation and not be deposited at another area, because this other area is hotter than the elevation. When the sodium which is not in vapour form is maintained evenly divided over the tube the experience gained with the "lamp with elevations" has shown that uniform distribution of the sodium which is present in vapour form in the discharge tube (during the operation of the lamp) is substantially always ensured. Irregular distribution of the sodium in the discharge tube in certain cases gives rise to the so-called "burning dark." This means that the discharge at certain areas is less bright than at other areas in the tube. This may even go so far that at certain areas substantially no sodium light is radiated, which is disadvantageous from a viewpoint of light technique and furthermore often provides a low output of the lamp.

2

A disadvantage of a "sodium lamp with elevations" of the kind referred to in the preamble is the large number of discontinuities that the discharge tube must be given to ensure satisfactory distribution of the sodium vapour. In a known 100-watt sodium lamp, for example, the number of elevations is ten, which requires a complicated manufacture.

An object of the invention is to arrive at a sodium lamp of the kind mentioned in the preamble in which the number of protuberances is small and nevertheless "burning dark" is avoided.

A low-pressure sodium vapour discharge lamp according to the invention comprising a discharge tube and an outer bulb surrounding it, wherein the space between the discharge tube and the outer bulb is substantially exhausted and wherein in the operating position of the lamp an amount of sodium which is not in vapour form is present in a protuberance of the discharge tube, which protuberance is heated only by the heat evolved in the discharge tube, is characterized in that the protuberance lies entirely outside the discharge space and that in the operating position the protuberance contains substantially the full amount of sodium which is not in vapour form, the following condition being fulfilled:

$$V > 0.5 \times A \sqrt{A}$$

wherein V is the volume (in ccm.) of the protuberance and wherein A is the surface area (in sq. cm.) of the orifice between the protuberance and the discharge space.

The term "discharge space" is to be understood herein to mean that portion of the discharge tube in which the discharge occurs during the operation of the lamp.

A surprising advantage of a lamp according to the invention is that "burning dark" does not occur, even if the above-mentioned elevations are absent.

The (large) protuberance of a sodium lamp according to the invention will be referred to as "appendix."

Another advantage of a lamp according to the invention is that it can be heavily loaded, that is to say it can absorb a high power. Consequently the amount of light per unit volume of the discharge tube (expressed, for example, in lumens per litre) can be considerable.

A lamp has a larger or smaller number of lumens per litre, dependent upon the electric power absorbed and the output. The number of lumens per litre of a lamp which is adjusted so as to have its maximum number of lumens/watts is referred to as the "G-value" of this lamp.

In a lamp according to the invention this G-value is higher than in a corresponding lamp which is not provided with an appendix. A corresponding lamp is to be understood to mean a lamp having the same dimensions, a similar thermal insulation and a similar igniting gas.

The appendix is preferably so formed that the condition $V > 2 A \sqrt{A}$ is fulfilled.

In this case there are more possibilities of adjusting the temperature of the sodium supply in the appendix to a value which is advantageous relative to the temperature in the discharge space.

It is naturally possible to provide a lamp according to the invention with more than one protuberance.

The properties of a lamp are found to depend inter alia upon the location of the appendix.

The protuberance is preferably located in the vicinity of an electrode of the discharge tube, since the efficiency

of the lamp, which is expressed, for example, in lumens per watt (the so-called specific light flux), is then higher than in the case of a different location of the appendix. If an appendix lies in the vicinity of the electrode the efficiency may, in practice, be equal to that of an otherwise corresponding lamp which is not provided with an appendix.

A sodium lamp according to the invention may be used, for example, for road lighting. If for this purpose use is made of lamps and fittings of the same size as before, the greater amount of light emitted by the new lamp permits of obtaining better road lighting, while the specific light flux when using a particular protuberance in the vicinity of an electrode may thus be substantially equal to that of a sodium lamp without the particular protuberance.

It is not quite clear why this particular protuberance near an electrode gives rise to such an advantageous result. On the one hand the separation between the mean temperature of the discharge tube and the magnitude of the pressure of the sodium vapour will play a part. In fact, the pressure of the sodium vapour in the operating condition will be determined by the temperature of the appendix, which is lower than the temperature of the discharge space. This separation is known per se for other lamps, for example, low-pressure mercury vapour discharge lamps. However, the specific light flux of these known lamps decreased upon introduction of a protuberance. A very surprising fact is that sodium lamps of the kind mentioned in the preamble allowed of a solution whereby this specific light flux can yet be maintained. Special dimensions of the protuberance and a special location thereof are found to be necessary for this purpose.

In a sodium lamp provided with an appendix in the vicinity of an electrode of the discharge tube, the orifice may be present, for example, at the level of this electrode.

Preferably, the portion of the protuberance which is most remote from the orifice lies nearest to the electrode.

With such a preferred solution there is only a small possibility of damage occurring to either the electrode or the appendix during the manufacture of the lamp.

The protuberance may have various shapes, for example, the shape of a spiralled cavity.

The protuberance preferably has the shape of a cylinder the axis of which extends approximately in parallel with the axis of the adjacent portion of the discharge space.

The protuberance then has the advantage of a simple shape, which is thus inexpensive. Due to the particular location of the cylindrical protuberance as referred to above, it is achieved that the cross-section of the discharge tube, inclusive of the appendix, can be small.

If the discharge tube is U-shaped the protuberance may be provided near a portion of one limb of the tube which is far remote from the other limb of the tube.

When using a U-shaped discharge tube the protuberance is preferably intersected by a plane of symmetry of this tube, which is at right angles to the plane which passes through the axes of the limbs of the discharge tube.

This embodiment affords the advantage that the appendix, together with the two limbs of the discharge vessel, can provide a great space factor of the cross-section of the outer bulb. The term "space factor" is to be understood herein to mean the ratio between the sum of the cross-sections of the two limbs of the discharge space and the cross-section of the appendix on the one hand and the internal cross-section of the outer bulb on the other hand. In this preferred embodiment the space factor can thus be great and hence the cross-section of the outer bulb can be small. The outer bulb can therefore be cheap and provide better thermal insulation.

The discharge space may have the shape of, for example, a circular cylinder with the protuberance located externally of the circular profile.

As an alternative, the protuberance can be so arranged as to find itself, at least partly, in a re-entrant part of the wall of the discharge space.

This preferred embodiment affords the advantage that the cross-section of the discharge space at the appendix, and inclusive the cross-section of the appendix, can be small. This total cross-section need not even be larger, or not much larger, than that of other portions of the discharge space. In this space the cross-section of the outer bulb can be small, and, if desired, substantially uniform throughout. This preferred embodiment is important, especially for linear lamps in which little space is usually available between the discharge tube and the outer bulb.

The protuberance has, for example, an axis which is substantially rectilinear so that the lamp can satisfactorily operate in one position or in a few positions.

To permit satisfactory operating of the lamp in any position, the low-pressure sodium vapour discharge lamp is given a protuberance which is worm-shaped, the axis of the protuberance, starting from the orifice, comprising successively the following portions:

A portion *a*, which turns away from an electrode and also turns away from a plane *P* which passes through the axis of the adjacent portion of the discharge space and the centre of the orifice;

a portion *b* which bends back towards plane *P*;
a portion *c* which intersects the plane *P*;
a portion *d* which turns away from the plane *P* the portions *d* and *b* being separated by the plane *P*;
a portion *e* which bends towards the axis of the adjacent portion of the discharge space, the distance from the said electrode decreasing.

An advantage of this solution is that, at any position of the lamp, an appendix portion lies lower than the orifice, so that sodium is prevented from flowing out of the appendix at any position of the lamp.

With the specified preferred solution the volume of the appendix will naturally have to be so much larger than the volume of the sodium that the sodium which is not in vapour-form cannot reach the orifice at any operating position.

In another embodiment of a lamp according to the invention the protuberance comprises a container and a supply tube from the orifice to the container, at least part of the supply tube extending into the container.

This embodiment, too, affords the advantage that the lamp can operate at several positions.

In the operating position of the lamp, before the invention had been made, a large excess of sodium had to be present (large relative to the sodium supply which is necessary for the discharge). This was because a considerable amount of sodium was necessary for ensuring even distribution of the sodium present in vapour form in the discharge tube, in order to avoid "burning dark." Before the invention had been made, each ccm. volume of the discharge tube required, for example, approximately 2 milligrams of sodium, of which only a fraction was used for the discharge.

In a lamp according to the invention less than a half milligram of sodium per ccm. volume of the discharge tube suffices.

In a lamp according to the invention the phenomenon of burning dark remarkably does not occur and therefore causes no problem any more. It has thus been found that the use of a lower quantity of sodium suffices, resulting in lower cost of sodium per lamp.

The sodium may be introduced into the discharge tube in several ways, for example, through an exhaust tube.

A low-pressure sodium vapour discharge lamp is preferably manufactured by a working method which utilises a capsule for introducing the sodium, which capsule contains the total amount of sodium required for the lamp and is sealed to the wall of the discharge space, establishing a free communication between the capsule and the discharge space in such manner that the capsule con-

stitutes the protuberance of the discharge tube, whereafter the capsule is heated.

This working method affords the advantage that the desired dose of sodium can be introduced into the lamp in a simple manner, since the possibility of drops of sodium remaining in a container or a supply duct, for example, an exhaust tube (to be severed afterwards) is now eliminated.

With the working method described, the sodium will preferably be protected by a suitable gas which has previously been led into the capsule.

Heating the capsule is desirable, in order to bring traces of sodium via the orifice of the protuberance immediately into the discharge space. As a result thereof, the lamp can rapidly assume its operating condition even when it is lit for the first time, since it is not necessary to wait for sodium which leaves the capsule due to the heat of the discharge of an igniting gas in the lamp.

The invention will be described with reference to the accompanying drawings, in which:

FIG. 1 is a perspective view of a sodium lamp according to the invention;

FIG. 2 is a cross-sectional view of the lamp, taken on the line II—II of FIG. 1;

FIG. 3 is a cross-sectional view of the lamp taken on the line III—III of FIG. 2;

FIG. 4 is a perspective view of part of a discharge tube of a lamp according to the invention provided with a worm-shaped appendix,

FIG. 5 is a perspective view, in part section, of a part of a discharge tube of a lamp according to the invention provided with an appendix with supply tube;

FIG. 6 is a longitudinal section of part of a linear sodium lamp according to the invention.

Referring now to FIG. 1, the reference numerals 1 and 2 indicate the lamp cap and the outer glass bulb, respectively, of a 220-watt low-pressure sodium vapour discharge lamp. Inside the outer bulb is a U-shaped discharge tube 3 having limbs 4 and 5 respectively. The portions of the limbs 4 and 5 which are adjacent the lamp cap 1 contain electrodes 6 and 7 respectively. The limb 4 of discharge tube 3 is provided with a protuberance 8 which ends into the rectilinear portion of the limb 4 via an orifice 9 (see also FIG. 3). A portion 10 of protuberance 8 which is remote from the orifice 9 is located in the vicinity of the electrodes 6 and 7. The portion 10, which is adjacent the said electrodes, contains an amount of sodium 11 which is fluid in the operating condition of the lamp.

Any steps taken for resiliently supporting the discharge tube 3 relative to the outer bulb 2 are not shown in FIG. 1.

FIG. 2 is a cross-sectional view, taken on the line II—II of FIG. 1, as viewed in the direction indicated by the arrow of FIG. 1.

FIG. 2 shows more details about the location of the protuberance 8 relative to the limbs 4 and 5 of the discharge tube. Corresponding elements of FIGS. 1 and 2 are provided with the same reference numerals. The space between the limbs 4, 5 and the appendix 8, on the one hand, and the outer bulb 2 on the other is substantially exhausted. The appendix 8 (see FIG. 2) is intersected by the plane of symmetry of the discharge tube, which passes through line 12 and is at right angles to the plane passing through the axes of the limbs 4 and 5.

FIG. 3 is a cross-sectional view of the lamp of FIG. 1 at the area where the protuberance 8 ends into the rectilinear portion of the limb 4 of the discharge tube. Corresponding elements of FIGS. 1, 2 and 3 are provided with the same reference numerals.

The lamp described with reference to FIGS. 1 to 3 has the data specified in the second column of the accompanying Table I. Corresponding data for a lamp which is not provided with an appendix are given in the third column of Table I.

6
TABLE I

	Lamp according to the invention (with appendix)	Lamp not according to the invention (without appendix)
5 Data		
Length of lamp (cm.)	111	
Diameter of lamp (cm.)	6.6	
Length of the discharge tube (cm.) (limb 4 and limb 5 together)	200	(1)
Internal diameter of the discharge tube (cm.)	1.9	
10 Volume of the discharge tube (litres)	0.57	
Length of appendix (cm.)	5	
Diameter of appendix (cm.)	0.6	
Volume of appendix V (ccm.)	1.4	(2)
Orifice a (sq. cm.)	0.28	
0.5 $A \sqrt{A}$ (cm.)	0.074	
15 Total amount of sodium in the lamp (milligrams)	250	1,100
Amount of sodium per ccm. in the discharge tube (milligrams)	0.44	1.9
Operating voltage of the lamp (volts)	275	275
Lamp current i (amps)	0.9	0.75
Power P (watts)	220	185
Light radiation of the lamp (lumens)	37,500	31,500
20 Number of lumens per litre (this is the G-value)	66,000	55,000
Specific light flux ϕ (lumens per watt)	170	170

¹ The same as in the previous column.

² No appendix.

³ For adjustment to maximum number of lumens per watt.

From Table I it can be seen that the lamp according to the invention produces approximately 19% more light than the corresponding lamp without appendix at the same value of the specific light flux.

FIG. 4 shows an example of an appendix for a lamp which may be able to operate at various positions.

FIG. 4 shows a portion 20 of a discharge tube of a lamp according to the invention having a lamp cap 21, an electrode 22 within the portion 20, and a worm-shaped appendix 23. The orifice of appendix 23 in the discharge space is indicated by 24.

FIG. 4 also shows a reference plane P, which is a flat plane passing through the axis 25 of discharge tube 20 and through the center of orifice 24.

When passing, starting from orifice 24, along the axis of protuberance 23 one finds successively:

a portion a which turns away from electrode 22 and also turns away from the plane P (portion a lies beneath the plane P);
45 a portion b which bends back towards the plane P;
a portion c which intersects the plane P at 26;
a portion d which turns away from the plane P;
a portion e which bends towards tube 20, the distance from electrode 22 becoming smaller.

No matter how the tube 20 is placed, there will always be a point of appendix 23 which lies lower than the orifice 24. This renders the said appendix suitable for lamps which must be able to operate at several positions.

FIG. 5 shows a portion 30 of a discharge tube of a lamp according to the invention having an appendix 31 shown in longitudinal section. The appendix comprises a container 32, which contains sodium 34, and a supply tube 33, part of which extends into container 32. The example of FIG. 5, too, is suitable for lamps which have to operate at several positions. If, for example, tube 30 is rotated in such manner that the appendix 31 with its container 32 becomes upright, then the sodium will accumulate between the portion of the supply tube 33 which extends into container 32, and the wall of container 32.

FIG. 6 shows another embodiment of a lamp according to the invention. 50 indicates one lamp cap of a sodium lamp having a rectilinear discharge tube 51, the outer bulb being indicated by 52. The cross-section of discharge tube 51 is similar at a short distance from electrode 53 than at a distance far remote from electrode 53 (far from lamp cap 50). In fact, the discharge space has, slightly beyond electrode 53, a re-entrant part or dent which accommodates part of an appendix 54. The orifice of the appendix in the discharge space is indicated by 55.

Since the appendix 54 is accommodated substantially within the re-entrant part of the discharge space, the diameter of the outer bulb 52 can yet be comparatively small.

The discharge space may, if desired, have further dents which do not accommodate appendices. It is also conceivable that a discharge space of a lamp according to the invention has a non-circular cross-section throughout or substantially throughout.

What is claimed is:

1. A low-pressure sodium vapour discharge lamp comprising a discharge tube and an outer bulb surrounding it, wherein the space between the discharge tube and the outer bulb is substantially exhausted and wherein an amount of sodium which is not in vapour form in the operating condition of the lamp is present in a protuberance of the discharge tube, said protuberance lying completely within the outer bulb and is heated only by the heat evolved in the discharge tube, said protuberance being entirely outside the discharge space and in the operating position containing substantially the full amount of sodium which is not in vapour form, the following condition being fulfilled:

$$V > 0.5 \times A \sqrt{A}$$

wherein V is the volume (in ccm.) of the protuberance and wherein A is the surface area (in sq. cm.) of the orifice between the protuberance and the discharge space.

2. A low-pressure sodium vapour discharge lamp as claimed in claim 1, wherein the following condition is fulfilled: $V > 2 A \sqrt{A}$.

3. A low-pressure sodium vapour discharge lamp as claimed in claim 2, wherein the protuberance is located in the vicinity of an electrode of the discharge tube.

4. A low-pressure sodium vapour discharge lamp as claimed in claim 3, wherein the portion of the protuberance which is most remote from the orifice lies nearest to the electrode.

5. A low-pressure sodium vapour discharge lamp as claimed in claim 4, wherein the protuberance has the shape of a cylinder the axis of which extends approximately in parallel with the axis of the adjacent portion of the discharge space.

6. A low-pressure sodium vapour discharge lamp as claimed in claim 5, in which the discharge tube is U-shaped, and the protuberance is intersected by a plane of symmetry of this tube, which is at right angles to the plane which passes through the axes of the limbs of the discharge tube.

7. A low-pressure sodium vapour discharge lamp as claimed in claim 5, wherein the protuberance is located, at least in part, within a re-entrant part of the wall of the discharge space.

8. A low-pressure sodium vapour discharge lamp as claimed in claim 1 in which the protuberance is worm-shaped, and in order to be able to operate the lamp at various positions, the axis of the protuberance, starting from the orifice, comprises successively the following portions:

a portion a, which turns away from an electrode and also turns away from a plane P which passes through the axis of the adjacent portion of the discharge space and the center of the orifice;
 a portion b which bends back towards plane P;
 a portion c which intersects the plane P;
 a portion d which turns away from the plane P, the portions d and b being separated by the plane P;
 a portion e which bends towards the axis of the adjacent portion of the discharge space, the distance from the said electrode decreasing.

9. A low-pressure sodium vapour discharge lamp as claimed in claim 1, wherein the protuberance comprises a container and a supply tube from the orifice to the container, at least part of which extends into the container.

10. A low-pressure sodium vapour discharge lamp as claimed in claim 9, wherein the lamp contains less than a half milligram of sodium per ccm. volume of the discharge tube.

11. A method of manufacturing a low-pressure sodium vapour discharge lamp comprising a discharge tube having a protuberance containing a supply of sodium which is not in vapour form during operation of the lamp, and an outer envelope surrounding the discharge tube and the protuberance comprising the steps of sealing a capsule containing the total amount of sodium required to the wall of the discharge tube, establishing a free communication between the capsule and the discharge space in such manner that the capsule constitutes the protuberance of the discharge tube, and thereafter heating the capsule to release the sodium.
